Primary Examiner — Karen E Kearney*Assistant Examiner* — Kristin E Reed(74) *Attorney, Agent, or Firm* — Terence P. O'Brien(57) **CLAIM**

We claim the ornamental design for a housing of a wrist-top computer, as shown and described.

DESCRIPTION

FIG. 1 is top, side perspective view of a housing of a wrist-top computer;

FIG. 2 is a first end view of the housing of FIG. 1;

FIG. 3 is a second end view of the housing of FIG. 1;

FIG. 4 is a first side view of the housing of FIG. 1;

FIG. 5 is a second side view of the housing of FIG. 1;

FIG. 6 is a top view of the housing of FIG. 1; and,

FIG. 7 is a bottom view of the housing of FIG. 1.

The broken lines shown in the drawings depict portions of the housing of a wrist-top computer that form no part of the claimed design.
